US0D1108637S

(12) **United States Design Patent** (10) **Patent No.:** **US D1,108,637 S**
(45) **Date of Patent:** **** Jan. 6, 2026**

(54) **AIR PULSE GENERATOR HOUSING**

(71) Applicant: **Hill-Rom Services PTE. LTD.**,
Singapore (SG)

(72) Inventors: **Jack Barney Sing**, Batesville, IN (US);
Mathieu Bernard, Pluvigner (FR);
Barry Eng Keong Tay, Singapore (SG);
Wei Bian, Singapore (SG);
Stacey Reuland, St. Paul, MN (US)

(73) Assignee: **Hill-Rom Services PTE. LTD.**,
Singapore (SG)

(**) Term: **15 Years**

(21) Appl. No.: **30/014,740**

(22) Filed: **Jul. 24, 2025**

Related U.S. Application Data

(62) Division of application No. 29/835,390, filed on Apr. 19, 2022, now Pat. No. Des. 1,089,626.

(57) **CLAIM**

The ornamental design for an air pulse generator housing, as shown and described.

DESCRIPTION

FIG. 1 is an isometric view of an air pulse generator housing in accordance with our design;

FIG. 2 is a front elevation view of the air pulse generator housing of FIG. 1;

FIG. 3 is a rear elevation view of the air pulse generator housing of FIG. 1;

FIG. 4 is a first side elevation view of the air pulse generator housing of FIG. 1;

FIG. 5 is a second side elevation view of the air pulse generator housing of FIG. 1;

FIG. 6 is a top plan view of the air pulse generator housing of FIG. 1;

FIG. 7 is a bottom plan view of the air pulse generator housing of FIG. 1; and,

FIG. 8 is another isometric view of the air pulse generator housing of FIG. 1.

(Continued)

The broken lines shown in the figures depict portions that form no part of the claimed design.
